UNITED STATES PATENT OFFICE.

LUTHER D. LOVEKIN, OF PHILADELPHIA, PENNSYLVANIA.

HEAT-INTERCHANGING APPARATUS.

1,235,908.

Specification of Letters Patent.

Patented Aug. 7, 1917.

Application filed June 5, 1916. Serial No. 101,673.

To all whom it may concern:

Be it known that I, LUTHER D. LOVEKIN, a citizen of the United States of America, and resident of Philadelphia, in the county 5 of Philadelphia and State of Pennsylvania, have invented a certain new and useful Improvement in Heat-Interchanging Apparatus, of which the following is a true and exact description, reference being had to the 10 accompanying drawings, which form a part thereof.

My present invention relates to heat interchanging apparatus of the well known type in which the exchange of heat between 15 two fluids is effected by causing one to flow through a group of tubes traversing a space into which the other fluid is passed.

The object of my invention is to provide apparatus of the type referred to, characterized on the one hand by its efficiency and 20 relatively large capacity per unit of bulk, and on the other hand by its inherent simplicity, durability and relative low cost of manufacture.

25 The various features of novelty which characterize my invention are pointed out with particularity in the claims annexed to and forming a part of this specification. For a better understanding of the invention, 30 however, and the advantages possessed by it, reference should be had to the accompanying drawings and descriptive matter in which I have illustrated and described the preferred embodiments of my invention.

35 Of the drawings:

Figure 1 is a sectional elevation of heat interchanging apparatus embodying a preferred form of my invention, the section being taken along the broken line 1—1 of 40 Fig. 2;

Fig. 2 is an elevation, viewed from the inner side, of one of the chambered end members;

Fig. 3 is an elevation, viewed from the inner side, of the other chambered end member;

Fig. 4 is a partial sectional elevation of one of the tubes of the retarding element with a portion of the retarding element 50 mounted therein;

Fig. 5 is an elevation of one of the tube sheets employed;

Fig. 6 is an elevation of a portion of one of the tube sheets with tubes mounted therein;

Fig. 7 is an elevation taken similarly to, but on a larger scale than Fig. 1, of a portion of the apparatus shown in the latter figure; and

Fig. 8 is an elevation with parts broken 60 away and in section, of apparatus generally like that shown in Fig. 1, but embodying a modified form of my invention.

The apparatus illustrated in Figs. 1 to 7 inclusive was primarily devised for use on 65 a locomotive to preheat the feed water supplied to the locomotive by the use of exhaust steam from the latter. It is to be understood, however, that the apparatus in the particular form shown, is adapted for many 70 other uses, and that my invention is generally applicable to heat interchanging apparatus of the general type referred to above.

In the particular apparatus shown in 75 Figs. 1 to 7, a plurality of parallel closely spaced tubes A, are expanded or otherwise rigidly secured at their ends to similar tube sheets B and BA. Secured to the remote or outer sides of the tube sheets B and BA, are chambered end members C and D respectively. Advantageously in some, though not in all cases the apparatus is formed as shown, with circular tube sheets and end members, and with the tubes arranged in a cylindrical mass. The chambered end member 80 C is formed with a rib or circular portion C' engaging the tube sheet B in a circular zone closely surrounding the tubes A. The end member D is similarly formed with a rib or portion D' engaging the tube sheet 85 BA. Advantageously in many cases the tube sheets may each be grooved as indicated at B', to receive a gasket F against which the corresponding end member portion C' or D' directly engages. Each of the end members 90 C and D is secured to the corresponding tube sheet by a series of stud bolts E screwed into threaded apertures formed in the tube sheet and extending in a circular series 95 closely surrounding the groove B'. The end member C is formed with internal webs C' engaging the tube sheet B at their free edges and dividing the space between the latter 100 and the outer wall of the end member proper

into an inlet compartment C^2 , an outlet compartment C^4 , and a compartment C^3 . The inlet and outlet compartments are of the same size and each half as large as the compartment C^3 which is separated from the chambers C^2 and C^4 by a diametral line. The end member D is provided with a single rib or web engaging the corresponding tube sheet along a diametral line in the same plane as the partition or web separating the chambers C^2 and C^4 of the end member C.

One of the fluids to be thermally acted upon, as for instance, feed water to be pre-heated, is admitted to the inlet compartment C^2 through the inlet opening C^5 , thence it passes through the group of tubes A communicating with the space C^2 to the chamber D^2 in the end member D. From there it returns to the chamber C^3 of the end member C through the tubes A connecting the latter chamber with the chamber D^2 . From the chamber C^3 the water again passes to the opposite end of the apparatus through the tubes connecting the chamber C^3 to the chamber D^3 , and from the chamber D^3 the water passes to the outlet chamber C^4 through the tubes A connecting the latter chamber to the chamber D^3 . The heated water passes out of the chamber C^4 through the outlet port C^6 .

To prevent the passage of the water in unbroken stream lines through the tubes A and hence to increase the heat transfer capacity of the tubes, I preferably extend through each tube, a retarding element G preferably formed by twisting a transversely corrugated metallic ribbon into a helix. To prevent axial displacement of the retarding elements, I form apertures through the projecting ends of the latter and thread or lace a wire through the apertures in the retarding elements G at the outer side of each tube sheet.

Surrounding the tubes A is a casing element I which in the preferred construction illustrated in Figs. 1 to 7, comprises a cylindrical body of wrought metal with outward flange portions I' at each end which may be of the same material as the body of the casing, and in practice are preferably formed separate from the latter and then welded thereto. Each flange portion I' comprises an outer portion abutting against the adjacent side of the corresponding tube sheet in a zone surrounding the bolts E and rigidly and permanently secured to the tube sheet as by the rivets J. As shown, the construction is strengthened by clamping the outer portion of the flange I' between the corresponding tube sheet and a washer like member K through which the rivets extend. Each end portion I' is advantageously curved generally as shown, for the double

purpose of increasing the flexibility of the flange and hence its capacity to accommodate relative thermal expansion and contraction of the tubes and the casing I, and to provide a clearance space between the ends of the bolts E and the flange portions I' in line therewith. The provision of this clearance insures against any disturbance of the connection between the casing I and the corresponding tube sheet in case a bolt E is caused to project through the tube sheet in the initial assembly of the apparatus or in any subsequent inspection or repair operation to which it may be subjected.

L represents a cast metal inlet casing secured to the body of the casing I communicating with the space inclosed by the latter through a port or ports formed in the casing body. Advantageously, the communication between the chamber in the inlet casing L and the interior of the casing I is through a series of relatively small ports I² formed in the casing body which serve to break up into small streams, the exhaust steam or other fluid admitted to the interior of the casing I. Similarly, an outlet casing M is secured to the under side of the casing I and the water of condensation or other fluid discharged from the interior of the casing I passes out of the latter through the port I³ into the outlet casing M and thence escapes from the apparatus ordinarily through piping secured to the casing M and communicating with the outlet port M' formed in the latter.

The apparatus disclosed in Figs. 1 to 7 is well adapted to attain the object of my invention as set forth above. The provision made for passing the water or other fluid flowing through the tubes A in series through a plurality of groups of these tubes provides a relatively long tube path and hence makes possible the relatively high velocity of flow through the tubes which is essential to secure commercially high rates of heat transfer. The rate of heat transfer is very substantially augmented also by the provision of the special retarding element G, and it is to be noted that with the construction described, in case of the destruction of some or all of these retarding elements from the erosive action of the water or other fluid passing through the tubes, especially when impure, it is possible to quickly renew the retarding elements or, if extra retarding elements are not available, the broken parts may be quickly and easily renewed and the apparatus thus left in operative form, though, with a reduced effectiveness. The desired relatively high efficiency and large capacity per unit of bulk thus secured is obtained, moreover, with a construction which is inherently simple, durable and relatively inexpensive to manufacture. The cas-

ing I may obviously be produced at a relatively low cost and by reason of its flexible flange portions I', possesses ample capacity for accommodating the effects of the relative 5 thermal expansion of the casing and the tubes. The connections between the outer portions of the flange portions I' and the corresponding tube sheet portions is a permanent one, the effectiveness of which is 10 in no wise impaired by such flexing of the inner portions of the flanges I' as are necessary to accommodate thermal expansion and contraction of the parts. The fact that these connections are permanent and are not 15 disturbed when the chambered end members are removed from time to time is of much practical importance. This avoids the difficulty of providing a satisfactory form of detachable connection between the flexible 20 flanges I' and the end members, and avoids the impairment of the flanges practically certain to result from repeatedly connecting them to and disconnecting them from the chambered end members, and of course 25 avoids unnecessary labor and expense in effecting such connections and disconnections.

While I prefer in many cases to form the body of the casing I of the same material as, and to integrally connect it to the flexible 30 flange portions I', I may also form the body of the casing of cast metal. In this case I connect the latter at one end at least, to the corresponding tube sheet by a separate flexible flange portion generally like the 35 flange portion I' of the construction shown in Figs. 1 to 7. Thus, in Fig. 8, I have illustrated an apparatus differing from that shown in Figs. 1 to 7 in that the casing body IA replacing the casing I of the construction first described, is formed at one end 40 with a rigid flange portion I¹⁰ secured to the adjacent tube sheet as by means of the bolts E employed to secure the corresponding end member D thereto. The body of 45 the casing member IA terminates at its other end a slight distance short of the tube sheet to which the end member C is connected. A flexible flange member IB which in its outer portion may be shaped like the 50 flanges I' may be and is shown as being connected to the tube sheet B exactly as is the flange portion I' of the construction first described. The flange portion IB comprises a cylindrical portion fitting about the 55 adjacent end of the casing IA and secured to the latter by rivets or screws O.

While in accordance with the provisions of the statutes I have illustrated and described the best forms of my invention now 60 known to me, it will be apparent to those skilled in the art that certain changes can be made in the form of my invention without departing from its spirit, and that some features of my invention can be used with-

out a corresponding use of other features.

Having now described my invention, what I claim as new and desire to secure by Letters Patent, is:—

1. Apparatus of the type described comprising in combination a plurality of tubes, a pair of tube sheets to which the opposite ends of the tubes are rigidly connected, a chambered end member secured to one of said tube sheets by a series of bolts extending around the portion of the tube sheet to which the tubes are connected and a casing surrounding the tubes and comprising an outturned flexible flange portion at one end which abuts against the last mentioned tube sheet and is secured thereto along a zone surrounding the bolts connecting said chambered end member and tube sheet. 75

2. Apparatus of the type described comprising in combination a plurality of tubes, a pair of tube sheets to which the opposite ends of the tubes are rigidly connected, a chambered end member secured to one of said tube sheets by a series of bolts extending around the portion of the tube sheet to 80 which the tubes are connected and a casing surrounding the tubes and comprising an outturned flexible flange portion at one end which abuts against the last mentioned tube sheet and is secured thereto along a zone 85 surrounding the bolts connecting said chambered end member and tube sheet and is separated by a clearance space from the zone of the tube sheet into which said bolts are secured. 90

3. Apparatus of the type described comprising in combination a plurality of tubes, a pair of tube sheets to which the opposite ends of the tubes are rigidly connected, chambered end members secured one to each 105 of said tube sheets by a series of bolts extending around the portion of the tube sheet to which the tubes are connected, and a casing surrounding the tubes and comprising an outturned flexible flange portion at its 110 ends each of which abuts against the corresponding tube sheet and is riveted thereto along a zone surrounding the bolts connecting the corresponding chambered end member to said tube sheet, and is separated by a 115 clearance space from the zone of the corresponding tube sheet into which said bolts are secured.

4. Apparatus of the type described comprising in combination a plurality of tubes, 120 retarding elements mounted in said tubes, tube sheets to which the opposite ends of the tubes are rigidly connected, chambered end members connected to the tube sheets each by a series of bolts surrounding the portion 125 of the tube sheet to which the tubes are connected, said end members being formed with inlet and outlet ports and partitions

arranged in conjunction with the tubes to provide a flow path comprising a plurality of passes between the two end members, and a casing surrounding the tubes and comprising an outturned flexible flange portion at its ends each of which abuts against the corresponding tube sheet and is riveted thereto

along a zone surrounding the bolts connecting the corresponding chambered end member to said tube sheet, and is separated by a 10 clearance space from the zone of the corresponding tube sheet into which said bolts are secured.

LUTHER D. LOVEKIN.
